UNITED STATES PATENT OFFICE

1,929,008

CORRUGATED RIBBED PAPER

Sidney D. Wells, Quincy, Ill., assignor to Paper Mills Laboratories, Inc., Quincy, Ill., a corporation of Illinois

Application June 22, 1928. Serial No. 287,598

2 Claims. (Cl. 154—33)

My invention relates to improvements in paper and more particularly to paper for corrugating purposes.

An important object of my invention is the provision of a paper for corrugating purposes which will result in a product having greater strength than the usual corrugated paper and which will be ornamental in appearance and inexpensive to produce.

10 Other objects and advantages of my invention will be apparent during the course of the following description.

In the accompanying drawing which forms a part of this specification and wherein like characters of reference denote like or corresponding parts throughout the same,

Figure 1 is a plan view of a portion of a section of corrugated paper embodying my invention,

20 Figure 2 is a longitudinal sectional view on the line 2—2 thereof,

Figure 3 is a transverse sectional view on the line 3—3 of Figure 2,

Figure 4 is a plan view of another form of my 25 invention,

Figure 5 is a similar view of still another form of my invention,

Figure 6 is a plan view of a portion of an indented flat for egg case fillers showing the application of my invention thereto, and

Figure 7 is a longitudinal sectional view of yet another form of my invention.

In the making of corrugated paper the trade has adopted a paper having a certain thickness 35 and weight. For example, the paper usually used has a thickness of .009 of an inch and weighs about 37 pounds per 1,000 square feet. I have discovered that the same weight of paper made in alternately thick and thin sections, or in other 40 words ribbed, will give a paper of greater strength for corrugating purposes if the corrugations and ribs bear a certain relation to one another, without the additional expense required by the use of a heavier paper.

45 In the drawing wherein for the purpose of illustration I have shown some preferred forms of my invention, the numeral 10 designates a sheet of paper having spaced parallel ribs 11 arranged longitudinally thereof and provided with corrugations 12 extending transversely of the paper and consequently at right angles to the ribs 11. It will be seen that any pressure exerted on the corrugations will be resisted by the greater thickness of the ribs and that paper made according 55 to my invention will have greater strength for the same weight of paper than the smooth paper heretofore used.

In Figure 4 the ribs are shown as arranged at 60 an angle less than 90 degrees to the corruga-

tions. This angle may be varied at will so that the ribs cross the corrugations.

In Figure 5 the ribs are arranged in criss-cross formation and produce a grid-like or diamond effect, which has great strength and is also ornamental in appearance.

In the form shown in Figure 6 the ribs are applied to indented flats 10' for egg case fillers and it will be seen that the strength of these flats is materially increased by this arrangement, the 70 ribs 11' extending into and crossing the indentations 12'.

Figure 7 illustrates a corrugated paper having the ribs 11 arranged on both sides of the paper.

It will be obvious that the ribs may be arranged in any shape or design so that they are at an angle to the corrugations. Not only will ribbed paper make a better corrugation sheet, but the use of ribs will make it distinctive and readily discernible by the trade. Distinctive water marks 80 may also be incorporated which will make it possible to recognize the manufacturer as well as add to the structural strength of the sheet.

The ribs or marks may be formed by using a cylinder mould of proper design, a dandy roll or 85 embossing rolls. The ribs are preferably made in the machine direction and the corrugations formed transversely of the machine direction.

The ribs are formed while the sheet is in a partially formed and moist condition and subject to flow on the application of local pressure. Consequently the material of the sheet will flow or be displaced to form a ribbed sheet having substantially uniform density throughout, as 90 shown in Figure 3.

While I have shown and described the preferred embodiment of my invention it is to be understood that various changes in the shape, size and arrangement of parts may be resorted to without departing from the spirit of my invention or the scope of the subjoined claims.

Having thus described my invention, what I claim and desire to protect by Letters Patent is:

1. A new article of manufacture comprising a sheet of ribbed paper having substantially uniform density throughout, said paper having corrugations therein arranged at an angle to the ribs.

2. A method of forming a paper sheet comprising forming spaced ribs on said paper in the direction of the paper making machine while maintaining substantially uniform density throughout the sheet, and corrugating said paper in a direction which is at an angle to the machine direction.

SIDNEY D. WELLS.
